PHONOGRAPHIC APPARATUS

Edward C. Conrad, Philadelphia, Pa., assignor to
Radio Corporation of America, a corporation of
Delaware

Original application January 31, 1939, Serial No.
253,920, now Patent No. 2,254,839, dated Sep-
tember 2, 1941. Divided and this application
October 30, 1940, Serial No. 363,397

5 Claims. (Cl. 274—1)

This invention relates to phonographic apparatus of the type used for recording sound on records adapted to be played back immediately after recording, and particularly to the mounting mechanism for the recording and reproducing device, the present application being a division of my copending application Serial No. 253,920, filed January 31, 1939.

In apparatus of this type, the recording head is generally mounted in such a manner that it has a fixed relation to the record. Thus, as the recording needle wears and needs resharpening, no compensation can be made for the shortened needle. Furthermore, in some cases, it is desirable to vary the depth of cut or to vary the angular relation between the cutter head and the record. It is, accordingly, the primary object of my present invention to provide an improved mount for the recorder whereby such adjustments may be made readily.

More particularly, it is an object of my present invention to provide a novel recorder head mounting which can be adjusted easily to vary the depth of cut of the recording stylus as well as the angular relation of the stylus relative to the record blank while maintaining the stylus in engagement with the blank.

According to my present invention, the recorder head is mounted on its carriage by means of an eccentric which may be turned in its bearings to provide desired vertical as well as angular adjustment of the recorder relative to the record in a plane normal to that of the record. Suitable locking means is provided for retaining the mechanism in the position to which it has been adjusted.

The novel features that I consider characteristic of my invention are set forth with particularity in the appended claims. The invention itself, however, both as to its organization and method of operation, as well as additional objects and advantages thereof, will best be understood from the following description of one embodiment thereof, when read in connection with the accompanying drawing, in which

Figure 1 is a side view, partly in section, showing the recorder and its mounting with the recorder head in recording position,

Figure 2 is a sectional view through the recorder head mounting taken on the line II—II of Fig. 1, and

Figure 3 is a sectional view taken on the line III—III of Fig. 2.

Referring more particularly to the drawing, wherein similar reference characters designate

corresponding parts throughout, there is shown a frame member 1 on which is rotatably mounted a feed screw 3 arranged to receive power from a motor driven turntable 5 through suitable gearing carried in a housing 7, the feed screw 3 extending across a record blank R on the turntable 5 when in operative position. Slidably and pivotally carried on the feed screw 3 is a carriage 9 to which is pivoted a combined feed and latching lever 11, the lowermost portion of the lever 11 being provided with a half nut 13 adapted to have driving engagement with the feed screw 3, as clearly shown in Fig. 1. The lever 11 is also provided with a lateral extension 11a terminating in an offset toe 11b which is adapted to be received by a correspondingly formed slot 14 in the frame 1, the slot 14 serving as a detent to latch the lever 11 when the latter is moved to latching position, as more fully described in my above noted copending application.

The carriage 9 has a pair of downwardly extending arms 9a constituting a support for the sound translating device shortly to be described and terminating in aligned rings 9b which rotatably receive a cylindrical mounting member 15 having a hollow, cut-away, intermediate portion 15a and solid, closed end portions 15b each formed with a diametrically extending slot 15c. Mounted eccentrically on the end portions 15b of the mounting member 15 with their axes parallel to the plane of the record R are a pair of aligned, conically-tipped bearing elements or screws 17 which pivotally support a cradle 19 to which is secured a sound translating device 21 that may be either a recorder, a reproducer, or a combined recorder and reproducer, the device 21 being provided with a suitable needle 23 for cooperation with the record R. A coil spring 25 having one end secured to the device 21 and the other end 40 to an adjustable screw 27 carried by the carriage 9 serves to counterbalance the weight of the sound translating device 21 on the record R.

To adjust the device 21 vertically or angularly with respect to the surface of the record R, as 45 when it is desired to vary the depth of cut of the needle or cutter 23, or to compensate for shortening of the cutter 23 when it has been sharpened, a thumb screw 29 on one of the bearing rings 9b is loosened and, by means of a screw driver inserted into one of the slots 15c, the mounting member 15 may be rotated in either direction, preferably within the limits determined by a pin 31 extending into a slot 33 in one of the end portions 15b of the member 15. It will be obvious 50 that, since the bearing screws 17 are eccentric

cally mounted on the ends 15b, they will be raised or lowered slightly as the member 15 is rotated, depending upon the direction of rotation, to correspondingly raise or lower the device 21 in a plane normal to that of the record. When, finally, the desired adjustment is obtained, the thumb screw 29 may be tightened again to releasably lock the device 21 in adjusted position. Obviously, this adjustment may be made while the cutter 23 remains in engagement with the record disc R.

From the foregoing description, it will be apparent that I have provided a simplified mounting mechanism for recorders and the like. No doubt, many modifications and changes well within the scope of my invention will readily suggest themselves to those skilled in the art. I, therefore, desire that my invention shall not be limited except insofar as is made necessary by the prior art and by the spirit of the appended claims.

I claim as my invention:

1. In phonographic apparatus, the combination of a support, a mounting member rotatably mounted on said support, a pair of axially aligned bearing elements carried on said mounting member eccentrically thereto, and a sound translating device pivotally mounted on said bearing elements and adapted to cooperate with a record, the rotation of said mounting member on said support serving to vary the relation of said sound translating device relative to the record.

2. In phonographic apparatus, the combination of a support, a mounting member rotatably mounted on said support for circumferential adjustment thereon, a pair of axially aligned bearing elements carried on said mounting member eccentrically thereto, and means for releasably locking said mounting member in any position of adjustment on said support.

3. In phonographic apparatus, the combination of a support, a mounting member rotatably mounted on said support for circumferential adjustment thereon, a pair of axially aligned bearing elements carried on said mounting member eccentrically thereto, a sound translating device pivotally mounted on said bearing elements and adapted to cooperate with a record, the rotation of said mounting member on said support serving to vary the relation of said sound translating device relative to the record, and means for releasably locking said mounting member in any position of adjustment on said support.

4. In phonographic apparatus, the combination of a pair of spaced supporting arms terminating in aligned bearings, a mounting member rotatably carried by said bearings for rotation on a fixed axis, a pair of axially aligned bearing elements carried by said mounting member in spaced relation to each other and in eccentric relation to said mounting member, and a sound translating device pivotally carried by said bearing elements and adapted to cooperate with a record, the rotation of said mounting member in said bearings serving to change the position of said bearing elements relative to said axis of rotation and thereby to vary the position of said sound translating device relative to the record.

5. The invention set forth in claim 4 characterized in that said mounting member is constituted by a hollow cylinder having closed end portions, said end portions being received in said aligned bearings, characterized further in that said bearing elements are mounted one on each of said end portions, characterized further by the addition of a cradle pivotally supported on said bearing element, and characterized still further in that said sound translating device is secured to said cradle.
